UNITED STATES PATENT OFFICE.

GIOVANNI EMANUELE ELIA, OF ROME, ITALY, ASSIGNOR TO VICKERS LIMITED, OF WESTMINSTER, LONDON, ENGLAND.

SUBMARINE MINE.

1,346,309.

Specification of Letters Patent. Patented July 13, 1920.

Original application filed September 6, 1917, Serial No. 190,095. Divided and this application filed December 9, 1918. Serial No. 265,827.

To all whom it may concern:

Be it known that I, GIOVANNI EMANUELE ELIA, a subject of the King of Italy, residing at Rome, Italy, have invented certain new and useful Improvements in Submarine Mines; and I do hereby declare the following to be a full, clear, and exact description of the invention, such as will enable others skilled in the art to which it appertains to make and use the same.

This invention relates to submarine mines of the kind comprising an anchor connected to the flotation chamber or mine proper by a mooring cable the paying out of which is effected by the separation of the flotation chamber from the anchor after the mine has been launched. This application is a division of an application filed by me on September 6, 1917 for patent on submarine mines, Serial No. 190,095 upon which Patent Number 1,299,440 was issued Apr. 8, 1919.

In the specification of my prior pending patent application No. 178,367, filed July 3, 1917 upon which Patent Number 1,296,376 was issued Mar. 4, 1919, I have described a construction of submarine mine in which a hydrostatic device is employed to release a slideable weight located at any desired point on the mooring cable so that the weight will fall and actuate a suitable device for stopping the unwinding or paying out of the cable from the anchor when the flotation chamber, owing to its buoyancy, has ascended far enough to occupy the required final depth of immersion.

According to this invention there is employed a buoy or float, in lieu of a hydrostatic device, which is connected to the weight by means of a cord or cable and is adapted to control the release of the weight at the proper moment so that the weight descends and actuates the device for stopping the unwinding or paying out of the mooring cable from the anchor. The length of the cord or cable connected to the weight is selected according to the final depth of immersion desired for the flotation chamber, and the upward pull of the buoy or float, prior to its reaching the surface of the water, retains the said weight in a position against a stop on the mooring cable. The said cord or cable for the buoy is attached to a spring controlled or other coupling device which is

so constructed that when the buoy (which may be released from the anchor in any suitable manner at any desired point during the descent of the mine ascends by its buoyancy and reaches the surface of the water, the pull which the buoy exerted on the cord or cable during its upward ascent no longer prevails, with the result that the parts of the coupling device become disengaged or separated, thus releasing the weight which then descends by gravity along the mooring cable until it reaches the anchor and actuates the device for stopping the unwinding of the said cable.

In order that the said invention may be clearly understood and readily carried into effect the same will now be described more fully with reference to the accompanying drawings in which:

Figure 1 illustrates diagrammatically various positions of the mine after being launched and finally coming to anchor with the flotation chamber at a predetermined depth beneath the surface of the water.

Figs. 2, 3 and 4 illustrate diagrammatically on a larger scale how the spring controlled coupling device is rendered active and the weight released during the ascent of the flotation chamber after the anchor reaches the sea bed.

Fig. 5 is a sectional view on a larger scale showing the mine as a whole.

Fig. 6 is a vertical section of the spring controlled coupling device shown on a still larger scale.

Fig. 7 is an enlarged view of the weight-releasing mechanism forming part of Fig. 6.

Fig. 8 is a vertical section of the buoy or float which controls the spring controlled coupling device.

Fig. 9 is a cross section through the anchor showing the winch-drum of the mooring cable and its locking device.

Fig. 10 is an end view of the said locking device in the locked position.

A is a mine body or flotation chamber, B is the anchor and C is the plummet. D is the mooring cable and E is part of the mooring cable winch drum. F is a short chain which connects the plummet to a spring controlled locking lever G. H is the spring controlled coupling device. I is the sliding weight normally held against a stop J on the mooring

cable D. K is the buoy or float which is connected to the coupling device H by a cord or cable L the length of which is selected according to the final depth of immersion desired for the flotation chamber A. M is a pivoted lever on the anchor B which lever is actuated by the falling weight I when the latter is released by the coupling device H.

The stop J is connected to the mooring cable D by a screw j , and fits over a tubular extension i of the sliding weight I; the weight I being detachably secured to the said stop by radially movable detents j' having chamfered inner ends which normally engage within a circumferential recess in the extension i , while their outer ends normally abut against the interior of a surrounding sleeve or cylinder h forming part of the aforesaid coupling device H. The said sleeve or cylinder h contains a spring h' which normally tends to force the cylinder into disengaged position as hereinafter described. Pivotaly connected at h^2 to the sleeve or cylinder h is a bell crank lever h^3 to one arm of which the cord or cable L is attached, the other arm carrying a split pin h^4 which passes through the cylinder h and by engaging within a slot i' in the weight I serves normally to lock the weight rigidly in place, the arrangement being such that when the buoy cord or cable L is rendered taut, the split pin h^4 will be withdrawn. Prior to the launching of the mine and during its descent, the buoy k , which is in the form of a pair of hollow cones joined at their bases, occupies an inverted position on the anchor as shown at b Fig. 1 and is adapted to float clear of the anchor by its buoyancy immediately the mine is launched. When the mine is launched and after the release of the float, the plummet C, in the example shown, continues to hold the lever G in engagement with the toothed rim e of the mooring cable drum against the influence of the spring g until it reaches the sea bed and its weight is removed from the lever G. The spring g thereupon disengages the lever G and releases the winch drum E (Figs. 2, 3 and 4). Owing to its buoyancy the flotation chamber A separates from the anchor and the mooring cable D is paid out. The buoy K, which has previously been released and which has separated from the flotation chamber by its buoyancy has in the meantime rendered the buoy cord or cable L taut, the tension thereon turning the cranked lever h^3 about its fulcrum and withdrawing the detachable pin h^4 which locks the weight I to the coupling device H. The cylinder h , under the influence of the buoyancy of the float then moves relatively to the weight I thus further compressing and energizing the aforesaid spring h' and during the separation of the flotation chamber and anchor and the ascent of the float and

the flotation chamber to the surface, the float continues to exert tension on the cord L and maintain the spring h' energized. When however the buoy or float reaches the surface, the pull which it exerted on the cord L no longer prevails and the spring h' reacts and moves the cylinder h downwardly until it is clear of the said stop J. The aforesaid detents j' are thereupon free to move radially outward, thus freeing the weight I and allowing it to fall by gravity until it is arrested by striking the lever M. The lever M is pivotally connected at m to the top plate of the anchor B and carries a part m' which normally bears upon or lies immediately above a shoulder m^2 on an arm m^3 which is pivoted at m^4 to the anchor and is normally held out of engagement with the toothed drum e of the mooring cable drum by a spring detent m^6 . When the weight I strikes the lever M the shock of impact forces the free end of the arm m^3 into engagement with the toothed drum e of the mooring cable drum thus stopping the further paying out of the mooring cable and the flotation chamber A remains anchored at the desired depth. The rate of the unwinding of the mooring cable D may be controlled in any suitable manner, for example, by the usual hydraulic brake (not shown) so that the buoy will precede the flotation chamber in the ascent of these parts through the water.

Means may be provided for causing the buoy K to sink after it has fulfilled its function; such means may comprise, for example, a tube k closed at both ends and containing a quantity of mercury k' , the closure at the outer end of the tube being constituted by a plug k^2 composed of a substance which is soluble by mercury. The tube k is formed with perforations k^3 at or about the center adapted to admit water to the interior of the buoy through the said tube after the plug k^2 at its outer end has been dissolved by the action of the mercury. The said perforations are protected by a concentric tube k^4 of smaller diameter than the main tube k , and located therein, said concentric tube being joined to the main tube toward the inner end thereof and left open at the outer end so that the mercury will flow over the surface of the inner tube and thus be prevented from escaping through the perforations when the tube is inverted and the mercury flows from one end of the outer tube to the other. Up to the moment of launching of the mine, or during the descent of the mine, as before stated, the buoy is inverted, the mercury remaining at the inner end of the tube k and out of contact with the plug k^2 . When however, the buoy is released from the anchor and assumes an upright position, the mercury k' comes into contact with the plug k^2

k^2 as shown at Fig. 8, upon which it acts and after a short interval eats through the plug, allowing water to pass into the interior of the buoy through the perforations 5 k^3 so as to destroy its buoyancy and cause it to sink. As water enters the buoy, the air within the buoy escapes therefrom through a passage provided with a non-return valve as is indicated diagrammatically in Fig. 8.

I claim:

1. A submarine mine provided with a float controlling the mechanism for anchoring the mine at a predetermined distance below the surface of the sea, said float being provided with a passage for admitting sea water to the interior thereof, soluble material normally closing the passage, a liquid within the buoy which, when brought into contact with the soluble material, dissolves it to permit the entrance of water into the buoy through the passage the relation of the parts being such that said liquid comes automatically into contact with said soluble material after the mine has been launched.

2. A submarine mine provided with a float for controlling the operation of the mechanism for anchoring the mine at a predetermined distance below the surface of the sea, said float being adapted to be submerged after it has performed its function by the provision of a passage to the interior of the buoy, a soluble material normally closing the passage, a liquid within the buoy capable of dissolving said soluble material, the connection of the float to the

parts controlled thereby being such that the float assumes in the water a position which causes said liquid to come in contact with the soluble material the relation of the parts being such that said liquid comes automatically into contact with said soluble material after the mine has been launched.

3. A buoy or float having means for admitting water when desired to the interior thereof, said means comprising a tube or chamber containing mercury and having an opening closed by a substance which is soluble in mercury, and the relation of the parts being such that the mercury comes automatically into contact with said substance until after the mine has been launched.

4. A submarine mine provided with a float controlling the mechanism for anchoring the mine at a predetermined distance below the surface of the sea, said float being provided with a passage for admitting sea water to the interior thereof, soluble material normally closing the passage, a liquid within the buoy which, when brought into contact with the soluble material, dissolves it to permit the entrance of water into the buoy through the passage, means for normally maintaining the float in such a position that said liquid is out of contact with said soluble plug the relation of the parts being such that after the mine has been launched said liquid comes automatically into contact with said soluble material.

In testimony whereof I affix my signature.

GIOVANNI EMANUELE ELIA.
